James M. Conklin, Peekskill, New York
Letters Patent No 189. dated June 27, 1868

The schedule referred to in these letters Patent and making part of the same

To all whom it may concern:

Be it known that I, James M. Conklin of the village of Peekskill in the County of Westchester and State of New York, have invented a new design for a stove for heating halls and rooms which is described as follows, reference being had to the annexed drawings of the same and which make a part of this specification.

Fig 1 represents the upper side of the bottom plate of said stove.

Fig 2 represents the upper side of a ring plate which is placed immediately over the fire chamber of the stove and which rests upon the cast iron sides and ends of the same.

Fig 3 represents an outside ^{side} view of the side plate which forms a part of the body of the stove.

28
Fig 4 is an outside view of the top plate.

The body of the stove between the ring plate (fig 2) and the top plate (fig 4) is made of sheet iron which is confined at the bottom by a flanch on the upper side of the ring plate, and at the upper end by a flanch on the under side of the top plate. The design in fig 1 consists of the peculiar form of the circumference of the bottom plate a a a a and also the peculiar form of the flanch b b b which latter corresponds with and receives the sides and end plates of the stove said flanch and also the figure around the circumference of said plate being in alto relief.

The design in fig 2 consists in the peculiar form of said ring plate in its circumference and also the ornamental scallop figure in bas relief of the edge of said plate c c c c.

The design in fig 3 is the ornamental figure in alto reliefed in the centre of the raised panel in the middle of said plate also the ornamental vine or leaves surrounding said panel e e e also the ornamental figures in alto reliefed d d d near the respective corners of said plate and also the ornamental figures l l in alto reliefed in the centre of the panels respectively near the ends of the plate.

What I claim as my invention and desire to secure by letters patent is the
